UNITED STATES PATENT OFFICE.

ALBURT D. PEJAUO, OF CLEVELAND, OHIO, ASSIGNOR, BY DIRECT AND MESNE ASSIGNMENTS, TO THE AMERICAN FOLDING MACHINE COMPANY, OF CLEVELAND, OHIO, A CORPORATION OF OHIO.

PAPER-FOLDING MACHINE.

972,469.

Specification of Letters Patent. Patented Oct. 11, 1910.

Application filed May 17, 1909. Serial No. 496,585.

To all whom it may concern:

Be it known that I, ALBURT D. PEJAUO, citizen of the United States, residing at Cleveland, in the county of Cuyahoga and

5 State of Ohio, have invented certain new and useful Improvements in Paper-Folding Machines, of which the following is a specification.

10 My invention relates to a new and original machine for folding sheets of paper of different sizes and with various folds, all substantially as shown and described and particularly pointed out in the claims.

15 Figure 1 is a side elevation of the machine. Fig. 2 is a vertical sectional elevation of the machine with the parts corresponding to Fig. 1. Fig. 3 is a side elevation of the machine at right angles to Fig. 2 and looking in from the left. Fig. 4 is a 20 rear elevation of the machine. Fig. 5 is a sectional plan view of the machine corresponding otherwise to Fig. 3. Fig. 6 is a cross sectional view of the group of creasing rolls through which the paper passes successively as a last step after being folded and when otherwise ready to be discharged from the machine and of other parts associated operatively therewith. Fig. 7 is a sectional elevation of the machine corresponding in 25 the main to Fig. 2 but with certain folding or tucking parts rotated to right angles as compared with Fig. 2. Figs. 8 to 16 inclusive are views of sheets of paper showing some of the fold lines possible with this machine. Fig. 17 is a face view of one of the plates W in full lines and showing a possible modification in dotted lines.

30 The object of this machine is more especially to fold relatively small sheets of paper, such as ordinary letter head, legal cap and like sheets, larger or smaller, but is not necessarily limited as to size of paper, so that printed sheets, circulars and the like within the size of a given machine can be 35 folded as rapidly as they come from the printing press and creased and delivered for any further purpose. It may be said that for ordinary purposes the machine is neither large nor expensive, and does not exceed say 40 two by three feet in plan, or smaller, and correspondingly small in elevation.

45 Referring now to the various parts, A represents the main frame of the machine and S the power or drive shaft, provided in this

55 instance with a hand wheel W' to rotate the same and operate the machine, but power may be used instead and be applied in any available way.

60 The top 2 of the table is of sheet metal, preferably, and constitutes a rigid portion of the main frame of the machine. Said top has a transverse slot or opening co-incident with vertical opening or slot 3 and which slot is adapted to receive and direct the sheet of paper folded by blade 6 down into 65 position to receive a second or double fold at transverse slot or opening 4 or through vertical slot 5. Said slots 4 and 5 have the form of a Maltese cross see Fig. 17 and both are adapted to receive blade 7 according to 70 its adjustment as will presently be seen.

75 The operating parts entering into the first and second foldings above mentioned comprise the blades 6 and 7, respectively. Blade 6 is removably supported at its ends in rack-bars R arranged vertically on opposite sides of the machine and adapted to run up and down with a reciprocating movement, like a sash, in suitable guide-ways in the machine frame. The operation of said rack-bars is 80 effected through a line of gears presently to be described. The travel of blade 6 is fixed by the travel of the rack-bars, and its fullest possible depth of stroke is down to the bottom of slot 3 between the side walls 85 W. The cross slots 4 and 5 are through these walls, and while blade 6 is adapted to run only in slot space 3, the blade 7 is rotatable upon its axis and may enter either slot 4 or 5 according to the direction of fold 90 desired. To this end said blade is provided with a supporting cross head H and a stem or shank E rotatably mounted in a bearing J in the main frame. Said bearing has an arm h, and a set screw h' is engaged through 95 a curved slot in plate 10 splined on said stem E and adapted to fasten said head in any rotary adjusted position of said head and its blade 7. The said stem or rod E is designed to receive a direct operating thrust 100 to carry the paper engaged by blade 7 into receiving position between the initial creasing rolls 12, and said thrust is effected through a suspended or swing arm F, having a transverse slightly curved slot 13 between its ends and at one end of which slot there is a side projection or roller 14, adapted 105 to be operatively engaged by a cam 15 on shaft

16. As said shaft and cam rotate the cam engages said projection 14 with each revolution and swings said arm forward with a thrust movement for blade 7. Said stem or 5 spindle E is rotatably supported in a small block 17 engaged on trunnions in bearings in the lower extremity of arm F, and is confined therein by a nut on its outer end and a shoulder on its inner portion bearing against 10 said block, and a spiral spring 18 on shaft E between said block 17 and plate 10 throws said blade 7 back to initial position when cam 15 has done its work. So it occurs that the second in the series of three folding 15 blades is adapted to produce a second fold in a once folded sheet by entering either slot 4 or slot 5 according to its position, and to this end is rotatably mounted in bearing J as above described and locked in either or 20 any adjusted position by screw h'. If for any reason the initial fold is not to be made by blade 6 said blade is removed and then the first fold will be made by blade 7 with the unfolded sheet in slot 3.

25 The rotatable setting of blade 7 to different angles of work implies a like capability of change in the single initial set of creasing rolls 12 which always work therewith and receive the paper from blade 7 in either 30 or any of its positions. Thus, in Fig. 1 said blade is shown as standing vertically in front of vertical slot 5 and rolls 12 are vertical likewise, while in Fig. 7 said blade is horizontal and said rolls 12 are horizontal 35 also, and the successive creasing rolls 19 and 20, and idler 21 and stackers 27 and 31 change with rolls 12 as will now be seen. Thus, G represents a rotatable supplemental frame in which said rolls are mounted upon 40 shafts engaged at their ends in said frame, and a trunnion or spindle g at the center of said frame axially opposite spindle E of blade 7 has a bearing in the main frame of sufficient depth and strength to operatively 45 support said frame and the parts thereon in any adjusted position. Then in order to fix said frame G when rotated I employ a bolt 22 engaged through any one of the three several holes m according to position. This 50 provides for both a quarter and a half turn of said frame G, which in the latter case reverses the position of the rolls and other parts from that shown in Figs. 1 to 6 inclusive. Assuming, now, for better understanding of the operation, that the said roll 55 carrying or supplemental frame G has been rotated from its most frequent using position, as in Figs. 1 to 6, to position, Fig. 7 with the said rolls horizontal, the thrust of 60 blade 7 through slot 4 will carry the sheet or paper into the bite of rollers 12, when said blade is immediately retracted. If there be no further folding to do when the paper has passed through said rolls 12 it is directed to 65 one side by means of a combined stop and

guide 24, Fig. 6, in the direction indicated by the arrow, and in this travel the paper is engaged by the star wheel 27, termed a "stacker," to deliver the same at one side. But in the event that still another fold is to 70 be formed in the paper the guide 24 is swung to or toward stacking wheel 27 see Fig. 7 so as to allow the paper to pass directly forward past the same into tucking position for blade 28 and engaging relation between the 75 second set of creasing rolls 19 and 20. Said so-called tucking or folding blade 28 is carried by arms 30 supported and operated as hereinafter described and is adapted to produce the third fold of the sheet or paper 80 which has been passed on from blades 6 and 7, and from rolls 19 and 20 the folded sheet is discharged between idler 21 and stacker wheel 31 working together. It will thus be seen that at least three different and distinct 85 folds for a given sheet are directly provided for in this mechanism with the necessary creasing of the sheet on all the fold lines successively, rolls 12 creasing the fold made by blade 6 as well as that made by blade 7, 90 and direction of the second and third folds as compared with the first by blade 6 depends on the positions of blade 7 in respect to slots 4 and 5.

Obviously there are numerous details in 95 connection with the construction and operation of the parts just described which have been passed over and will now be considered. Thus, as a means of operating the rack-bars R which carry blade 6 I provide reversely 100 rotatable gears 36 36' mounted on frame A and meshing with said bars. Said gears are adapted to rotate in reverse directions a given distance successively and are driven from power shaft S by gear 38 thereon meshing with gear 39 on crank shaft 16, Figs. 3 and 5, and which carries the actuating cam 15 for blade 7. Said shaft 16 has a crank 40 at one end, and on this crank is engaged one end of a rack-bar 41, seen in inclined position Fig. 2, and provided with a slot lengthwise having rack teeth on one edge meshing with a pinion 43 running in said slot. Said pinion is rigid with one gear 36 on the same stud or support 39', see Fig. 3; and serves to 110 rotate said gear first in one direction and then in the opposite direction according as the said rack 41 reciprocates in its engagement with pinion 43. Then in order that the two rack-bars R for blade 6 shall work uniformly together I interpose a shaft 44 and place gears 37 and 37' of the same size thereon on opposite sides of the machine and thereby reach rack controlling gear 36' on the opposite side of the machine and which 115 corresponds to gear 36 on the initial side of the machine and meshing with gear 37. Gear 36 is thus made to engage one rack-bar R directly and the other of said bars indirectly. Again, the several paper creasing 120

rolls above described are rotated at a predetermined speed by power from the main shaft and through numerous intermeshing gears as seen in plan, Fig. 5. As to these 5 gears it may be said in advance that they may be more or less variously related or geared up one with another and still work out the desired rotation of said rolls, but in this instance I have followed an apparently 10 natural order of selection and transmission and which proceeds from or through the shafts 46, 47 and 48, Fig. 5, to gear 50 as the initial gear in the planetary group. Said several shafts 46, 47 and 48 are oper- 15 atively connected by bevel gears at their ends, and shaft 46 is connected with like gears with main or power shaft S, so that when the said shafts rotate the creasing rolls and stackers operated thereby are rotated also. 20 From initial pinion 50 in the group transmission proceeds through pinions 51 to 52, and then from 51 through idler 53 and thence forward without a break to 54, 55, 56, 57, 58 and 59 successively. Pinion 56 like- 25 wise is an idler, pinions 57 and 58 belong to the two rolls 12, and pinion 59 to stacker 27. Pinions 52 and 55 belong to rolls 19 and 21, pinion 51 to roll 20 and pinion 54 to stacker 31. Again, a line of actuating mechanism 30 for the third blade or tucker 28 is provided as hereinbefore indicated so as to actuate said blade in timed relation with preceding parts, and consists in a shaft 60, Fig. 5, which has bevel gear connection with power 35 shaft S to drive the same and is provided with a cam 61 at its other end which engages the end of a tappet rod 62. Said rod engages arm 30 on one end of a vertically disposed rod 64 mounted in frame G with a 40 thrust movement and which shaft has an arm 30' on its other end corresponding to arm 30, and the third folding blade 28 is fixed somewhat freely in or to these arms at its ends so as to get the desired action. Said 45 arms with their blade have a limited swinging or oscillating movement together, first to carry said blade to tucking position between rolls 19 and 20 and then back under the action or effect of spring 65 on axially 50 rotatable rod or shaft 64 which carries arms 30 and 30', see Fig. 2. The tappet rod 62 is itself loosely mounted in a sleeve 70 resting on trunnions on frame A, so that said rod can be removed or swung out of the way 55 when the creasing rolls are rotated to position Fig. 7. Then cam 61 actuates tappet rod 72, Fig. 4, and which engages a pivoted lever 73 adapted to engage arm 30 of the tucking blade 28 in the same place and way 60 as said rod 62.

An adjustable stop 35 is shown as adapted to run in slot 3 for the paper and serve as a stop therefor when needed, as in the case especially when unfolded sheets are intro- 65 duced in said slot.

Respecting the walls W, the said walls may have any suitable construction and be of any suitable material, the need being that they should hold the paper in either single sheets or with a single fold imparted by 70 blade 6, and the two walls need not necessarily be alike but the walls next to creasing rolls 12 must be such as to enable the paper to be thrust through the slot or slots therein by blade 7 and assist in the folding of the 75 paper as this occurs. Likewise any suitable top 2 may be used, as well as suitable paper guides 75 and a stop plate 76. Top 2 is slotted transversely to permit guides 75 and their lock nuts 77 to be laterally adjusted 80 and whereby the paper may be variously placed relatively to vertical slot 5 in plates W and also to blade 7, and stop plate 76 is also adjustably secured to top 2 by lock nut 78 in slots 79 in said plate and top 2, re- 85 spectively. Plate 76 is thereby adapted to be set at any given point on table top 2 to stop the paper so that it may rest in any desired position relatively to slot 3 and blade 6, and whereby the first fold may be made 90 at any given point in the paper between its side or end edges and dependent upon whether it is fed endwise or sidewise thereto. Blade 6 is also adjustably secured vertically in slots r in rack bars R by thumb screws r' 95 or their equivalent. Thus blade 6 may be variously set so that it will fold and deliver a sheet of paper with its fold line at different elevations relatively to the horizontal slot 4 in plates W, thereby providing for 100 variations in further folding operations by blades 7 and 28, respectively. By these means the fold lines can be made in any portion of the sheet P and in either or both directions thereon as may be desired, such, 105 for example, as is seen in Fig. 12 which shows a single fold and which is produced by blade 7 passing through slots 4 and doubling the sheet at its middle and then discharging the same through casing rolls 110 12 by stacking wheel 27. Fig. 10 shows a double fold and wherein both blades 6 and 7 participate and the paper is discharged by stacker 27, as before. Fig. 11 illustrates a three-fold, and in this case the sheet is so 115 fed to the table that blade 6 will strike the paper off center and then blade 7 will strike on one of the two cross fold lines and carry it into position to be folded upon the other line by blade 28 and discharged past 120 stacker 31. Fig. 13 illustrates a form of fold wherein all three of the several blades participate and represents an eight page fold adapted especially for booklets. In this case the fold line a—a is made by blade 125 6, and the fold line b—b by blade 7. This represents a four-fold sheet until blade 28 strikes the same in the middle and which corresponds to line c—c and tucks the paper into rollers 19 and 20, whence it is discharged 130

1 by the stacker 31. Numerous other folds are possible with this mechanism, as is also in part illustrated in the several undescribed views and which folds would appear obvious 5 from the foregoing description and need not therefore be more particularly referred to. Other folds also are possible, as likewise would appear obvious.

10 Cross reference is made to a joint application filed by Albert D. Pejau and John J. Zeitz, Ser. No. 581,521, which contains some of the features of construction and operation embodied in the present invention and is an improvement thereon and not 15 in conflict therewith.

What I claim is:

1. In paper folding machines, a set of blades adapted to fold the paper in succession, the first blade arranged vertically and 20 the second blade having a central axis on which it is adapted to rotate to different working angles, and means coöperating with said blade to fold the paper at different angles according to the adjustment of said 25 blade.

2. In a paper folding machine, a folding blade having a stem by which it is rotarily and slidably mounted, a pivoted actuating arm engaging said stem and adapted to give 30 a thrusting movement to said blade, and a spring adapted to restore the blade to initial position.

3. In a paper folding machine, a folding blade mounted edgewise in a head having a 35 stem and a fixed portion of the machine frame in which said stem is slidably and rotatably mounted, to different folding positions, a pivoted arm loosely engaging the end of said stem, means to actuate said arm 40 at regular intervals and impart a thrusting movement to said blade and a spring on said stem to retire the blade after a stroke has been made.

4. The combination of a folding blade 45 having a supporting head and stem and a bearing in which said stem is slidably and rotatably mounted, means to fix the blade in any given working position engaging said stem and means to thrust the blade forward 50 and to retire the same successively.

5. In a machine for folding paper, a folding blade adapted to be set at different angles and creasing rolls adapted to be set at the same angles as said blade and to receive 55 the folded paper therefrom.

6. In a machine for folding paper, a folding blade variously adjustable as to the angle of fold, a set of creasing rolls correspondingly adjustable to receive the paper 60 from said rolls, said blade and rolls being axially mounted opposite each other.

7. In paper folding machines, a rotatable folding blade, in combination with a plurality of sets of creasing rollers and a tucking folder for the paper between said sets of 65

rolls and rotatable therewith to working relations with said first named blade.

8. In a paper folding machine, a main frame and a roller carrying frame rotatably mounted therein, in combination with a rotatable folding blade having its axis of rotation directly in line with the axis of said roller carrying frame, and means to fix said parts in operative relations one with the other. 75

9. In a paper folding machine, a main frame and a supplemental frame rotatably mounted therein, creasing rolls therein in sets arranged to operate in different planes at an angle to each other, a tucking blade for 80 the paper mounted between said sets of rolls and means to reciprocally operate said blade carried by said supplemental frame. 85

10. In a paper folding machine, a rotatably mounted frame and two sets of creasing rolls therein, means to direct the folded paper from one set to the other comprising a tucking blade and means to reciprocally actuate said blade comprising tappet mechanism and a spring. 90

11. In a machine for folding paper, three several folding blades set to fold at different angles successively and two of said blades rotatably adjustable, in combination with 95 creasing rolls adapted to coöperate with said rotatable blades in all their positions.

12. A machine for folding paper, having three several folding blades set to fold at varying angles successively, the second of said blades provided with a shaft with 100 which it is adapted to be rotated to different angles, in combination with a rotatable frame having said third blade mounted therein, and creasing rolls supported in said frame in advance of and after said third blade, respectively. 105

13. In a machine for folding paper, a plurality of folding blades adapted to operate at an angle to each other successively, in combination with a rotatable frame carrying one of said blades, two sets of creasing rolls in said frame arranged in advance of and behind said last mentioned blade successively, and said frame adapted to be inverted. 110

14. In a machine for folding paper, two sets of creasing rolls, a folding blade between said sets of rolls and a rotatable frame in which said blade and rolls are mounted, in combination with a rotatable stacking device operatively related to each set of rolls and means to operate said rolls and stacking devices having operating connection through the axis of said frame. 115

15. In a paper folding machine, a table 120 having a slot across the same adapted to receive paper to be folded and parallel walls coincident with said slot and having intersecting slots through the same adapted to be used to further fold the paper, in com- 125

bination with a plurality of folding blades adapted to work in said slots, and one of said blades having an adjustable mounting adapting said blade to work in either of said 5 intersecting slots in said walls.

16. In a paper folding machine, a table having a slotted opening through which the paper to be folded is fed, a wall coincident with one side of said slot having slots at 10 different angles to said slotted opening and adapted to receive the paper from said slotted opening.

17. In a paper folding machine, a table having a slot across its top and vertical 15 walls coincident with the edges of said slot and extending downwardly therefrom with a space between them and provided with transverse slots traversing said space at different angles, in combination with a blade 20 adjustable to said transverse slots respectively and rolls to receive the paper from said blade.

18. In a machine for folding paper, a main frame having a top with a downwardly 25 opening slot therein, opposite walls coincident with the edges of said slot and spaced apart substantially the width of said slot and said walls provided with slots angularly related to each other, in combination with a 30 vertically reciprocating folding blade and a second folding blade rotatable to operate through any one of the said slots in said walls.

19. In a paper folding machine, a main 35 frame and a top having a transverse slot open downward and fixed walls coincident with said slot having slots through the same at different angles and with a common center, in combination with an axially rotatable 40 folding blade adapted to be thrust through either of said slots, means to adjust said blade to working position, and means to reciprocate the blade.

20. In a paper folding machine, a main 45 frame having vertically disposed walls spaced apart to the top of the machine and said walls having intersecting slots there- through and guides and stops adjustably fixed upon said top and adapted to be ar- 50 ranged to receive sheets of different sizes, in combination with a reciprocating folding blade adapted to enter said walled space from the top of the machine and impart a single fold to the paper and a single adjust- 55 able blade mounted to reciprocate at right angles to said walls through either of said intersecting slots.

21. In a machine for folding paper, the combination of a vertically reciprocating 60 folding blade, a folding blade having a head and stem on which it is rotatably mounted and located next in succession to said vertically reciprocating blade and adapted to be set at different angles, means to rotatably 65 fix said rotatable blade comprising a part

engaged with said stem and a set screw to fasten said part and hold said blade when adjusted, and means to operate said blade comprising a pivoted arm freely engaged with the end of said stem and a cam to vi- 70 brate said arm.

22. In a machine for folding paper, the main frame of the machine, a blade having a stem provided with a bearing in said frame on which the blade is rotatable, means to 75 fix said blade in any rotated position, a pivoted arm and a pivoted support therein for the end of said stem, and means to vibrate said arm comprising a rotatable cam and a spring to return the said parts to starting 80 position.

23. In a machine for folding paper, a main frame and a rotatable frame mounted therein, a pair of creasing rolls supported in the ends of said rotatable frame and a 85 folding blade located between said rolls, a shaft and arms rigid therewith supporting said blade at its ends, a spring adapted to throw said blade back to starting position, and tappet mechanism adapted to engage 90 one of said arms in any of the adjusted positions of said rotatable frame.

24. In a machine for folding paper, a table having a walled space across the same open to the top of the machine and the walls 95 of said space having intersecting horizontal and vertical slots therethrough, an adjustable stop in the said space at either side of said vertical slot, means to independently adjust said stops, and a single adjustable 100 folding blade adapted to pass through either of the slots in said walls.

25. In a paper folding machine, separately mounted folding blades arranged to fold a sheet of paper into a series of folds and 105 adapted to operate successively upon said sheet, one of said blades adjustably related to the other blade to fold the paper either on parallel lines or on angular lines and means to operate said blades and means coöperat- 110 ing with said blades to produce the folded product.

26. A paper folding machine comprising two folding blades disposed at right angles to each other, one of said blades being ro- 115 tatable to coöperate with the other blade to fold the paper either on parallel lines or on lines at an angle to each other, and means to actuate said blades and means coöperat- 120 ing with said blades to produce the folded product.

27. A machine for folding sheets of paper having reciprocating folding blades dis- 125 posed at different angles in respect to a given plane, and creasing rolls for the paper com- bined with said blades, one of said blades being adjustable to different-working posi- tions in respect to the paper and to said creasing rolls.

28. A paper folding machine having fold- 130

- ing blades adapted to operate successively and separately adjustable in respect to each other on independent axes, and rollers co-operating with said blades to form finished 5 folds.
29. A paper folding machine comprising a rotatable folding blade adapted to be set in different predetermined working positions at angles to each other, means to rotatably fix said blade and means co-operating with said blade to produce the folded 10 product.
30. A paper folding machine having a folding blade mounted at one edge on a rotatable support and adapted to be set in different planes, and a set of creasing rolls adapted to be adjusted to receive the paper 15 from said blade in all its positions.
31. A paper folding machine having vertical and horizontal reciprocating blades respectively, and a set of creasing rolls to receive the paper from said horizontal blade, said horizontal blade being placed between 20 said rolls and said vertical blade and independently rotatable supports for said horizontal blade and said rolls to permit different 25 working positions between said parts.
32. A paper folding machine comprising three several folding blades arranged to fold 30 a sheet of paper at different angles successively, and creasing rolls intervening the latter two of said blades and said rolls and the last blade having a joint rotatable support adjustably mounted in respect to the 35 other blades.
33. A paper folding machine having a plurality of folding blades and a plurality of creasing rolls adapted to operate in succession, one of said blades and also said rolls 40 being adjustable rotarily to predetermined different-working positions in respect to the line of presentation of the paper thereto.
34. A paper folding machine comprising a folding blade, a rotatable adjustable support and creasing rolls following said blade 45 and stacking mechanism for the paper next after said creasing rolls mounted upon said support and comprising two rotatable members adapted to work together and one of 50 said members having teeth about the same.
35. A paper folding machine comprising a plurality of folding blades and one of said blades rotarily adjustable and means to fix 55 said adjustable blade at different predetermined working angles, in combination with creasing rolls adjustable to co-operate with said adjustable blade in its different angles, and rotatable stacking devices in opposed relations to said rolls.
60. 36. A paper folding machine comprising a series of folding blades and one of said blades adjustable to work at different predetermined angles, and creasing rolls adjustable to conform to the changed positions
- of said adjustable blade, in combination with 65 a guide for the folded paper next after said creasing rolls and a tucking device and set of creasing rolls next after said guide, and a stacker after each of said sets of creasing rolls.
37. The combination in a paper folding machine of a plurality of paper folding blades arranged to operate at right angles to each other successively and a set of creasing rolls after each blade, the last of said 70 blades being adapted to tuck the paper in the latter of said sets of rolls, a roller and a rotatable stacker adapted to receive the paper from said last named rolls, and rotarily adjustable supports for said blades, 75 rolls and stacker.
38. The combination of a rotarily adjustable folding blade and a set of creasing rolls and a stacker for the paper, rotatable to work with said blade in its changed positions, and a guide to deflect the paper 80 from said rolls to said stacker.
39. In a paper folding machine, a folding blade and a head in which said blade is engaged provided with a shank and bearings in which said shank is rotarily mounted, and means to adjust said parts to cause 85 the blade to work in different planes at an angle to each other, in combination with co-operative folding means alined with said 90 blade in all its different positions.
40. In a paper folding machine, a folding blade and a head carrying the same having a shank mounted to receive a sliding thrust, means to fix said blade to work at different 100 angles and means to impart a thrust thereto, in combination with means to hold the paper having slots at an angle to each other and adapted to receive said blade.
41. In paper folding machines, a machine 105 having a folding blade and a head in which said blade is adapted to be rotatably fixed at different predetermined angles and means to thrust said blade forward in said head and to restore the same after a thrust has 110 been made, in combination with rolls rotatably mounted and adapted to be alined with said rotatable blade in its different working angles.
42. In a machine for folding paper, a 115 folding blade and a shank carrying the same rotatable in fixed bearings, in combination with a pivoted arm to operate said shank, a cam adapted to swing said arm in one direction and thereby impart a thrust to said 120 blade and a spring to retract the blade, and a rocking bearing in said arm having said shank mounted therein and means adapted to supply the paper to said blade and to receive the folded paper therefrom.
43. In a machine for folding paper, a 125 folding blade and a bearing in which said blade is rotatably adjustable to different

planes, in combination with a set of creasing rolls adapted to receive the paper from said blade and adapted to be rotated together to different planes according to the position of said blade.

44. A paper folding machine comprising a main frame and a supplemental frame rotatably adjustable therein and creasing rolls mounted on said supplemental frame and a reciprocable creasing blade rotatably mounted on an axis co-extensive with the axis of said rotatable frame.

45. A paper folding machine comprising a main frame and a supplemental frame rotatably adjustable therein, a paper folding blade rotatably mounted on said main frame and creasing rolls mounted on said supplemental frame, and means to adjust said supplemental frame to bring the said creasing rolls in working alinement with said blade in all its varying adjustments.

46. A paper folding machine comprising a main frame and a supplemental frame rotatable therein, and a folding blade and creasing rolls operatively supported on said supplemental frame.

47. A paper folding machine comprising a main frame and folding blades mounted therein, one of said blades being adjustable to fold at varying angles, in combination with a supplemental frame rotatably mounted in said main frame and creasing and stacking rolls in said supplemental frame, said supplemental frame being adapted to be turned to bring one of said sets of creasing rolls into alinement with said adjustable blade.

48. A paper folding machine having a main frame and a supplemental frame provided with a spindle on which it is rotatably supported on said main frame, rollers mounted on said supplemental frame and driving connections therefor mounted on said supplemental frame and operatively engaged with said spindle, in combination with a rotatably adjustable paper folding blade adapted to feed the paper to said rolls and means to supply the paper to said folding blade.

49. In a paper folding machine, a guide-way for the paper, a folding device mounted at one side of said guide-way and adjustable to varying angles in respect thereto, and

means coöperating with said device in all its angles to form a finished fold.

55

50. A paper folding machine having a fixed guide-way for the paper and a folding blade adjustable to varying folding positions at right angles to said guide-way, in combination with mechanism coöperating with said folding blade on the opposite side of said guide-way to finish the fold.

51. In a paper folding machine, a rotatably mounted head and a folding device and a stacking device mounted on said head and jointly adjustable to a plurality of different operating positions relatively to a fixed plane, in combination with means to supply the paper to said device including a folding blade rotatable from a given position to operate at different angles.

52. In a paper folding machine, a folding device adjustable to a plurality of different folding angles relatively to a given plane, in combination with means coöperating with said device to form a fold and a stacking device adjustable to the same positions relatively to which said folding device is adjusted.

53. In a paper folding machine, means to fold a sheet of paper and devices adapted to produce a further fold therein comprising a folding member adapted to be adjusted to produce folds at varying angles to its original folding position, and rolls coöperating with said folding member.

54. A paper folding machine having a guide-way for the paper, in combination with a device adapted to produce a fold parallel with or at an angle to two opposite edges of the paper, or parallel to or at an angle to the other two edges, and coöperating mechanism to complete the fold.

55. In a paper folding machine, means to fold a sheet of paper in a given plane, in combination with means adapted to produce a fold parallel to said original fold, said means being axially adjustable so as to produce a fold at an angle to said original fold.

In testimony whereof I affix my signature 100 in presence of two witnesses.

ALBURT D. PEJAUO.
